UNITED STATES PATENT OFFICE.

ADOLPH G. BECKMAN, OF BALTIMORE, MARYLAND.

HAIR-CURLER.

1,178,987.

Specification of Letters Patent. Patented Apr. 11, 1916.

Application filed January 14, 1913. Serial No. 742,037.

To all whom it may concern:

Be it known that I, ADOLPH G. BECKMAN, a citizen of the United States, residing at Baltimore, in the State of Maryland, have 5 invented new and useful Improvements in Hair-Curlers, of which the following is a specification.

This invention relates to hair curlers; and it has for its object the provision of a 10 device of this character which may be constructed from a single length of wire bent to provide a main receiving portion for initially receiving the hair during the curling operation and a confining portion terminally 15 provided with a receiving hook which is adapted to engage one end of the receiving portion so as to hold the confining portion and the receiving portion in proper hair confining and curling positions relatively. 20 Another object of the invention is the provision of a fastener wherein the hair receiving portion will be extended for a distance beyond the engaging hook of the confining portion so as to facilitate winding the 25 hair around the receiving portion during the operation of connecting the device with the hair.

With these and other objects in view, the invention consists of certain novel features 30 of construction, combination and arrangement of parts, as will be hereinafter described and claimed.

In the accompanying drawings:—Figure 1 is a perspective view of the curler; Fig. 35 2 is a similar view, showing the receiving portion released from the confining portion and illustrating the manner of curling the hair around the receiving portion; and Fig. 3 is a section on line 3—3 of Fig. 1.

With a view to maximizing the curling efficiency of the device with a minimum use 40 of material, I preferably construct the curler from a single length of wire having a flat side 1 and a curved side 2. This construction has been found to lend sufficient rigidity 45 to the coöperating elements of the curler and is also admirable in that the device may be associated with the head without scratching or otherwise injuring the head. The material 50 is bent upon itself in its main length and provided with a loop 3, which is adapted to furnish elasticity which will be sufficient to spring the confining and receiving portions 4 and 5 respectively when the latter is dis- 55 connected from the locking terminal of the former.

The confining portion 4 is abruptly curved, as at 6, into the loop 3, and as illustrated said portion is curved longitudinally and provided at its free end with a hook 7 60 having a tongue 8, which is spaced relatively of the adjacent surface of the confining portion and disposed slightly below the plane thereof so as to facilitate the entrance of the locking end of the hair receiving portion 65 of the device after the curler is properly associated with the hair.

The free end of the portion 5 of the device has a width exceeding the slot 6^a which is formed between the abruptly curved portion 6 of the hook and the tongue 8 thereof. 70 This arrangement, it is seen on reference to Fig. 3 will prevent the accidental passage of the free end of the said portion 5 out of the hook. In order to release the portion 5 from the hook it will be necessary to manipulate the same so as to permit the free end of said portion 5 to be disposed in a position at right angles to the position shown in Fig. 3, as will be readily understood. 75

The hair receiving portion 5 is straight throughout, and as illustrated the free end of said receiving portion is extended beyond the hook 7 of the confining portion, so as to 80 facilitate initially guiding the hair onto the receiving portion after the winding operation. 85

In using the device, the hair is dampened, 90 and the device associated with the head with the confining and receiving portions 4 and 5 respectively separated relatively at their free ends. Under the inherent elasticity of the metal, the portions 4 and 5 at their free ends will be spaced for a distance sufficient 95 to permit the hair to pass beneath the hook 7. The hair is then wound around the extreme end of the receiving portion 5 and then gradually shifted in the length of the receiving portion until the entire portion 100 of hair is entirely wound and confined between the loop 3 and the hook 7. The extended end of the receiving portion 5 is then associated with the hook 7 and under the office of the loop 3 said extended portion 105 will be directed against the bight 9 of the hook. The portions 4 and 5 are then compressed against the windings of the hair and after a certain period of time the device 110 may be removed and the hair made to assume a curly, wavy and fluffy condition.

It is to be understood that material of any

desirable gage may be employed in the manufacture of the device and that devices of any desired proportion may be formed.

From the foregoing description, taken in connection with the accompanying drawings, the construction and operation of the invention will be readily understood without requiring a more extended explanation.

Various changes in the form, proportion and the minor details of construction may be resorted to without departing from the principle or sacrificing any of the advantages of this invention, as claimed.

Having thus described my invention, what

16 I claim is:—

The herein described hair curler comprising a spring rod doubled to form an intermediate spring loop and a pair of arms extending from the terminals of the loop, one 20 of said arms being formed with a loop at its outer end at right angles thereto and

open at a point at one side of said arm, the other arm being relatively wide in one dimension and relatively narrow in another dimension, cross sectionally, of such length, 25 as to enable it to project through the last named loop and with its least dimension about equal to the width of said opening and with its greater dimension normally at right angles to said opening, so that casual disengagement of the last named arm from the last named loop is prevented and it is rendered necessary to present the least dimension of said arm to the opening of said loop in order to disengage said arm from 30 35 said loop.

In testimony whereof I affix my signature in presence of two witnesses.

ADOLPH G. BECKMAN.
